UNITED STATES PATENT OFFICE

2,208,515

ELECTRIC TOKEN DELIVERY DEVICE

Bert E. Mills, Oak Park, Ill., assignor to Mills Novelty Company, Chicago, Ill., a corporation of Illinois

Application September 25, 1937, Serial No. 165,623

20 Claims. (Cl. 312—46)

This invention relates to electrically operated devices for delivering tokens, checks, coins, or the like. An object of the invention is to provide such a device, of relatively simple and inexpensive construction, in which the closing of any one of a plurality of remote-control switches will control the operation of the delivery mechanism so as to cause the latter to deliver a number of tokens or coins corresponding to the value which has been assigned to the particular switch that has been closed.

The invention is applicable to money-changers and to check-controlled amusement games of the type in which the operator, by the use of skill in the playing of the game, may cause the closing of one of a plurality of remote-control switches, respectively controlling the delivery of tokens or checks in varying number, whereby the further play of the game is facilitated by the delivery to the player, in numbers commensurate with his skill, of tokens or checks usable to unlock the playing mechanism for further play.

An object of the invention is to utilize a token ejector which is in the form of a rotatable disc having pockets adapted to receive tokens from a magazine and translate them to a delivery opening. Such an ejector may deliver the same number of tokens from each pocket, the total number depending upon the number of pockets from which delivery is made, or may deliver varying numbers of tokens from different pockets which are constructed to provide varying capacity, the latter arrangement having the advantage of greater compactness.

Another object of the invention is to provide an arrangement in which a complete cycle of movement, resulting in a coin or token delivery, is initiated each time a remote control switch is closed.

The present invention makes it possible to achieve the foregoing objects in connection with the use of the type of ejector mentioned, by providing for rotating the ejector a complete revolution each time the device is operated, so as to bring it back to the same initial position each time without retrograde movement. This is preferable to allowing an element as heavy as an ejector of the type contemplated, to return to its initial position by retrograde oscillation.

Variation in the amount of the delivery is effected by the provision of means for restraining delivery of the tokens from the ejector during a portion of its revolution, such means being adapted to release tokens under the variable control of a plurality of remote control circuits. A ro-

tatable commutator is provided, which is common to all of the control circuits, such commutator controlling the operation of motor means which continues to advance it until it opens the particular circuit which has been energized by the closing of a remote control switch, and also controlling the operation of the release mechanism in accordance with the extent of its own advance.

Other objects of the invention will become apparent from consideration of the following detailed description in connection with the accompanying drawings, in which:

Figure 1 is a plan view of a token delivery mechanism embodying the invention;

Figure 2 is a longitudinal, sectional view through the same, taken on the line 2—2 of Figure 1;

Figure 3 is a horizontal, sectional view of the same, taken on the line 3—3 of Figure 2;

Figure 4 is a schematic diagram of a device embodying the invention;

Figure 5 is a plan view of a modified form of the invention;

Figure 6 is a side elevation of the modification shown in Figure 5;

Figure 7 is a horizontal, sectional view taken on the line 7—7 of Figure 6;

Figure 8 is a horizontal, sectional view, taken on the line 8—8 of Figure 6;

Figure 9 is a vertical, sectional view taken as indicated by the line 9—9 of Figure 8;

Figure 10 is a wiring diagram of the modified form; and

Fig. 11 is a sectional detail taken substantially on the section line 11—11 of Fig. 3.

I have shown in the drawings an illustrative embodiment of the invention comprising a device provided with a series of remote-control switches, which are indicated at S1, S2, S3, S4, S5, S6, S7, S8, S9, and S10 in Figure 4. If used in a conventional money-changing device, each of these switches would be equipped with an appropriately designated key so as to control the payout of varying numbers and denominations of coins. If used in connection with an amusement game of the type, for example, commonly known as pin games, each of the switches may be associated with an opening or pocket for receiving a ball played by a player who, if skillful enough, may be able to cause the ball to drop into one of the pockets designated with a high value, so as to receive a correspondingly high number of tokens. For example, the switch S1 may be designated to cause delivery of one token,

the switch S2 to cause delivery of two tokens, the switch S3 to cause delivery of three tokens, etc.

Turning now to the mechanism shown in Figures 1 to 4 inclusive, there is provided an ejector disc 11, rotatably mounted upon a stud 12 projecting upwardly from a base plate 13 upon which the delivery mechanism is mounted. The ejector disc 11 is provided with a series of circumferentially spaced openings or pockets 14, each of which is adapted to receive a token or tokens from a magazine 15 in which the tokens are stored. The magazine 15 is mounted in a shoe 16, which in turn is secured, as by means of screws 17, to the lower side of a plate 18 fixedly associated with the base plate 13 by means of screws or bolts 19 and spacing washers 20 (Figure 3).

In the base plate 13, offset laterally from the discharge mouth of the magazine 15, and beneath the end of the shoe 16 opposite from the magazine 15, is a token delivery port 21. The magazine 15, the discharge port 21, and the ejector pockets 14 are all located equidistantly from the axis of rotation of the disc 11 so that the pockets 14 may first register with the discharge mouth of the magazine 15 to receive tokens therefrom and thence register with the discharge port 21 to allow such tokens to drop through the port 21 when the latter is open.

The port 21 is adapted to be closed by a gate 22, pivoted at 23 to the underside of the base plate 13, and controlled by a solenoid 24 coacting with an armature 25 which is connected by a link 26 to an arm 27 of the gate 22. The gate 22 is adapted to swing around its pivot 23, from a position beneath the discharge port 21 to a position wherein the port 21 is open for the full area of a pocket 14. It may be noted in this connection that one side of the port 21 opens into a slot 28 which is disposed on an arc about the pivot 23, and that the gate 22 is provided with a seat 29 extending upwardly to the level of the upper face of the base plate 13 and adapted to substantially fill the port 21 when the gate is in closed position so as to allow tokens carried by the pockets 14 to slide smoothly across the port 21, supported upon the smooth upper face of the seat 29 in doing so.

Means are provided for causing the ejector disc 11 to rotate a full revolution upon the closing of any one of the remote-control switches S1, S2, etc., for closing the gate 22 at the start of such revolution, and for thereafter causing a delayed opening of the gate 22, the period of delay depending upon the control switch that has been closed, and for holding the gate 22 open until the disc 11 has completed the remainder of its revolution, whereby the number of tokens delivered will depend upon the number of pockets 14 which pass across the port 21 after the gate 22 has been opened. This mechanism will now be described.

Secured to the ejector disc 11 and rotatably mounted on the stud 12 is a ratchet wheel 30 having a plurality of ratchet teeth 31, the number of teeth, for convenience, equalling the number of switches S1, S2, etc. The ratchet wheel 30 is rotated by means of a reciprocating drive bar 32 (Figure 1), slidably mounted between rollers 33 journaled on studs 34 threaded into the plate 18, and held down by washers 35 also mounted on the studs 34. Projecting downwardly from the bar 32 is a pin 36 (indicated in dotted lines in Figure 1) which engages between the furcations (Figure 3) of a fork 38, the hub 39 of which is journaled upon the stud 12. Pivoted at 40 to the

fork 38 is a pawl 41 which is held in yieldable engagement with the teeth 31 of the ratchet wheel 30 by means of a coil spring 42 secured at 43 to the pawl 41 and at 44 to the fork 38.

The drive bar 32 is actuated in one direction by an armature 45 of a solenoid 46, and in the other direction by a coil spring 47, secured at one end to a bracket 48 attached to the plate 18, and, at its other end, to a pin 50 by means of which the drive bar 32 is pivoted to the armature 46. The solenoid, when energized, draws the armature 45 in the direction indicated by the arrow 51, and the spring 47, when the solenoid 46 is de-energized, returns the drive bar 32 to its initial position. During the movement toward the solenoid, the pin 36 of the drive bar 32 swings the fork 38 in the direction indicated by the arrow 52, and the pawl 41 will thereupon rotate the ratchet 30 through an arc corresponding to the length of one of the teeth 31. During the return movement, the pawl 41 will ride over the tooth following the one that has been engaged and drop behind said following tooth in position to engage the same upon the next reciprocation of the drive bar 32.

The solenoid 46 is supplied with electric current through wires 53 and 54 (Figures 1 and 4). In the wire 54 there is inserted a switch 55 mounted in a casing 55' supported on a bracket 56 secured to the plate 18 and having an actuating lever 57 projecting over the drive bar 32.

As long as the circuit including the wires 53 and 54 is closed at all points other than the switch 55, the solenoid 46 will be intermittently energized in the following manner: The switch 55 is normally closed by the engagement of the actuating lever 57 by an arm 58 of a U-shaped actuator 59 secured to the drive bar 32. The spring 47 tends to hold the bar 32 in a position in which the actuator 59 will thus hold the switch 55 closed. Thus when the remainder of the circuit is closed, the solenoid 46 will be energized, causing the drive bar 32 to move in the direction 51 to its extreme advanced position in which the second arm 60 of the actuator 59 will engage the lever 57 to open the switch 55. This will open the circuit until the spring 47 has returned the drive bar 32 to its normal rest position, thus causing the switch 55 to be again closed, and the cycle of operations just described will be repeated until the circuit is broken elsewhere.

The opening and closing of the gate 22 is controlled by a commutator 63, which is mounted upon the reduced upper end 61 of the stud 12. The commutator 63 is mounted upon a ratchet wheel 62 through the medium of a spacing washer 64 to which it is secured by rivets 65. The assembly of ratchet wheel 62 and commutator 63 is supported by the engagement of the hub 66 of the ratchet wheel upon a shoulder 69 formed between the enlarged lower portion of the stud 12 and the reduced upper portion 61 thereof, and is held down by a washer 70 and screw 71 extending through said washer 70 and threaded into the upper end of the reduced portion 61 of the stud.

A pawl 72 (Figure 1) is pivoted at 73 upon the drive bar 32, and engages the teeth 74 of the ratchet wheel 62, being yieldingly held in such engagement by a coil spring 75 attached at 76 to the arm 77 of the pawl 72 and at 78 to the drive bar 32.

A retaining pawl 79 is pivoted at 80 to the plate 18, and engages the teeth 74 to retain the

commutator assembly in each step of its oscillation from initial to final position.

The commutator 63 includes a disc 66 of insulating material and, secured thereon, a contact 5 sector 81, against the flanged periphery 82 of which a plurality of brushes 83 are engaged, one for each of the remote-control switches S1, S2, etc. Wires 84 connect the respective brushes 83 to the respective switches S1, S2, etc., through the 10 medium of a suitable terminal block 85.

The primary purpose of the commutator is to regulate the opening and the closing of the gate 22. To this end, the commutator is connected by means of a wire 86 and a wire 87 to the solenoid 24 which actuates the gate 22, and the length of time the solenoid is energized depends upon the 15 particular remote-control circuit which has been closed, all of such circuits clearing through the commutator 63, as is apparent from an inspection 20 of Figure 4.

For example, if the switch S4 has been closed, calling for the delivery of four tokens, a circuit 25 will be established through the wire 84 leading from the switch S4, and the contact 83 connected to said wire, thence through the contact sector 81, the wires 86 and 87, the solenoid 24, and the wire 88 to the source of current 89, the latter being connected through a master switch 90 and the wire 91 to the bank of switches S1, S2, etc.

Simultaneously, another circuit will be established, as will hereinafter be explained in detail, through the drive solenoid 46, whereupon the latter will commence to oscillate the ratchet wheel 62 through the medium of the pawl 72, in step-by-step movements, advancing the ratchet wheel 62 one tooth 74 at a time. When six steps 35 of such movement have been completed, the contact sector 81 will have been oscillated to a position where it has broken contact with the brush 40 83 associated with the switch S4. The gate 22, which was closed at the beginning of the cycle of movement, will thereupon be allowed to open by the de-energization of the solenoid 24, and the ejector disc 11 continues to rotate, as will hereinafter more fully be explained, and will thereupon commence to discharge tokens through the discharge port 21, until a complete revolution 45 of the disc has been made. Since the gate 22 remained closed during six steps of movement, the number of tokens delivered will be those carried by the remaining four pockets 14.

The means for causing the commutator to rotate comprises two circuits for energizing the solenoid 46, one a starting circuit and the other 55 a running circuit. The starting circuit comprises a brush 95a, a wire 86 connecting the same to the main commutator sector 81, the brush 83, wire 84, and switch S4 (or whichever control switch has been closed), the wire 91 and master switch 90, the source of current 89, the wire 88, the solenoid 46 and its operating switch 55, the wire 54, and a sector 93 of a secondary commutator including an insulating disc 67 on which the sector 93 is mounted. The sector 93 has a 60 depending flange 94 which is contacted by the brush 95a. When the commutator has made one step of rotation, the starting circuit is deenergized by the moving of the sector 93 out of contact with the brush 95a. The running circuit 65 simultaneously picks up the load of supplying current to the solenoid 46. This circuit comprises the brush 95, a wire 96 connected thereto, the wire 91, the master switch 90, the source of current 89, the wire 88, the solenoid 46 and its operating switch 55, and the wire 54 connecting the 70

switch 55 to the sector 93. This circuit will remain closed irrespective of the opening of the gate control circuit, until the full number of steps of movement have been completed.

After the cycle of movement has been completed, 5 the commutator will remain in the final position until released by a manual release lever 97 (Figure 2) pivoted at 98 on a bracket 99 secured to the plate 18, and adapted to engage the heel 100 of the pawl 79. As it thus moves 10 the pawl 79 away from the ratchet wheel 62, the pawl 79 will in turn move the pawl 72 away from the ratchet wheel 62, and the latter will then be returned to its initial position by a coil spring 101 (Figure 1), attached at 102 to the ratchet wheel 15 62, and to an ear 103 on the bracket 99. This will cause the commutators to oscillate back to initial position. Simultaneously with the release of the pawls, the master switch 90 is opened by the link 90a connected to lever 97 (Figure 1). The 20 release lever 97 may be connected, in a game, to the mechanism for releasing the balls for further play of the game.

In order that the ejector disc 11 may stop at the end of each step of movement with its respective pockets 14 in proper registry with the magazine 15 and discharge port 21 respectively, I provide a locating pawl 105 pivoted at 106 to the base plate 13 (Figure 3) and having the triangle-shaped nose 107 engageable in V-shaped notches 30 108 in the periphery of the disc 11. The pawl 107 is yieldingly urged against the periphery of the disc 11 by the spring 109 coiled around the pivot pin 106, engaging a pin 110 mounted in the pawl 105, and, at its other end, engaging a lug 111 on 35 the base plate 13.

The ratchet wheel 62 has approximately twice as many teeth as the ratchet wheel 31, so that the ejector disc 11 may rotate a complete revolution while the commutators rotate only approximately one-half revolution. 40

In the form of the invention shown in Figures 5 to 9 inclusive, a plurality of coin-delivering gates 22a are pivoted at 112 in slots 113 in the ejector 11a which otherwise is similar in construction with that in the form of the invention hereinbefore described. 45

When in closed position, the gates 22a form bottoms for the pockets 14a, and it is contemplated that the number of coins handled by one 50 pocket may be different from the number of coins handled by another pocket, the difference being arranged for by locating the gates 22a at different levels below the top of the ejector 11a, as indicated in Figures 7 and 9.

Means for selectively opening the gates 22a comprise a rotatable selector 118 having upwardly projecting fingers 117 adapted to be selectively oscillated into a position intersecting the rotative path of fingers 116 projecting downwardly from arms 115 on the respective gates 22a. The fingers 116 and 117 are progressively varied in length in the order of their peripheral arrangement, so that the first of the fingers 117 will engage only one of the fingers 116 to open a 60 single gate, the second of the fingers 117 will engage the first and second of the fingers 116 to open the first and second gates, etc. 65

Each gate 22a is urged toward a closed position by a coil spring 114 coiled around its pivot 70 112, the respective ends of the coil spring engaging the fingers 116 of gate 22a and the ejector 11a.

The selector 118 is selectively controlled so as to bring any one of the fingers 117 into operative position, by the commutator which, in this form 75

of the invention, comprises a plurality of contact brushes 119 mounted upon the upper end of the shaft 120, the lower end of which carries the selector 118. The moving of the commutator 5 and operating member 118 into selective position is accomplished in a step-by-step manner by a repeating solenoid 46a having an armature 46a pivoted at 121 to a reciprocating drive bar 122 slidably mounted between guide rollers 123 on 10 the upper side of the plate 18a. A coil spring 124 secured at one end to the drive bar 122 and at its other end to the plate 18a, advances the drive bar 122, thereby causing the pawl 125, pivoted at 126 upon the bar 122, to move the ratchet 15 wheel 127 one notch ahead and thereby rotate through one step of movement the shaft 120, on the intermediate region of which the ratchet wheel 127 is secured. The pawl 128, pivoted at 20 129 to the plate 18a, is urged by a spring 130 into engagement with the ratchet wheel 127 to hold the same in each of the positions to which it is thus moved.

The panel 131 of insulating material is mounted above the ratchet wheel 127 on posts 132 secured to the plate 18a, and carries a plurality of pairs of contacts, each including an inner contact 133 and an outer contact 134, each pair being electrically connected together. The inner contacts 133 are contacted by the brushes 119 25 and the outer contacts 134 are contacted by a brush 135. Each of the contacts 133 is connected to a wire 84a of the remote-control circuit hereinbefore described.

If the circuit calling for the dispensing of a 30 single token is energized by the closing of switch S1, the commutator will advance one step, causing the last of the brushes 119 to leave the contact 133 which has thus been energized by the wire 84 of this No. 1 circuit. This will cause the 35 circuit to be broken and the commutator to stop in the first of its advanced positions. In this advanced position of the commutator, the shaft 120 will have carried the operating member 118 to a position where the No. 1 finger 117 is disposed in the path of the No. 1 finger 116. The 40 ejector 11a will then be caused to rotate a complete revolution, by a small electric motor 136, mounted on the plate 18a. Said motor 136 has a worm 137 engaging a worm wheel 138 on a 45 shaft 139 journaled in brackets 140 on the motor 136. To the shaft 139 is secured a disc 141 which carries an eccentric pin or roller 142 in driving engagement in a slot 143 with a bracket 144 secured to the ejector drive bar 32.

50 The motor 136 is controlled by the brush 135 which, in any of the advanced positions of the commutator, establishes through one of the contacts 134, a circuit in parallel with the circuit to the solenoid 46a. To this end, the brush 135 is connected to the motor through a wire 145, the other side of the motor being connected by means of a wire 146 to the wire 88a, which, through a wire 53a connects the solenoid 46a to the main circuit including the current supply 55 89a and master switch 90a. This circuit continues on through the several control switches S1, S2, etc., the wires 84a, the commutator 119, 133, the wire 86a, and the solenoid actuating switch 55a, and the wire 54a, back to the solenoid 46a. The brush 135, being positioned one step behind the last of the brushes 119, will move onto the live contact 134 while the last brush 119 moves off the corresponding live contact 133 and onto a dead contact 133.

75 Thus it will be seen that the circuit to the

motor 136 is not established until after the circuit to the solenoid 46a is broken—i. e., the motor 136 commences to operate after the commutator has moved up to the selecting position.

The mechanism connecting the drive bar 32a to 5 the ejector 11a is similar to that described in connection with the form of the invention shown in Figures 1 to 4 inclusive, and the same reference characters are therefore used to denote the 10 parts thereof.

If a control circuit subsequent to the No. 1 15 circuit is energized, as, for example, by the closing of switch S4, the commutator, as it is moved to each of the intervening positions, will continue to establish the circuit through the solenoid 46a owing to the fact that there is a brush 119 for each one of the contacts 133, and succeeding brushes will engage the live contact until the last brush has left the same.

The circuit through the motor 136 is broken 20 at the end of a complete revolution of the ejector 11a, by the action of a cam 148 formed on the periphery of the ejector 11a, engaging a lever 149 pivoted at 150 upon the base plate 13a, and having its opposite end 151 in engagement with 25 a pin 152 mounted in the drive bar 122 and projecting through a slot 154 (Figure 9) in the plate 18a.

Movement of the pin 152 by the arm 151 will cause the slide bar 122 to be once again reciprocated, without the assistance of the solenoid 46a, and, as a result, the commutator will be advanced one more step, thereby causing the brush 135 to move off the live contact 134 and onto a dead one, thus breaking the circuit 35 through the motor 136 and causing the revolution of the ejector 11a to stop.

The mechanism is reset for a subsequent operation by the resetting lever 97a, pivoted upon the bracket 159 and having its lower end engaged in a slot 164 in a slide bar 153 (Figure 8). The bar 153 is slidably mounted on the upper side of the plate 18a just beneath the ratchet wheel 127 by means of a screw 155 extending through a slot 156 in the bar 153 and threaded into the 45 plate 18a, and at its other end by means of the post 132 which extends through a slot 157 in the bar 153. A spring 158 attached at one end to the bar 153 and at its other end to a bracket 159 projecting upwardly from the plate 18a, normally maintains the bar 153 in the position shown in Figure 8. During the resetting operation, the lever 97a moves the bar 153 toward the pawl 128, whereupon a cam lug 160 on the bar 153 will engage a pin 161 depending from the pawl 128 55 and will move the latter out of engagement with the ratchet wheel 127. Simultaneously the end of the pawl 128 will move the pawl 125 out of engagement with the ratchet wheel 127. The pawl 125 is normally urged into engagement with 60 the ratchet wheel 127 by a spring 162 attached at one end to the arm 163 of the pawl 125 and at its other end to the drive bar 122.

Release of the ratchet wheel 127 allows the spring 101a to oscillate the commutator and 65 selector assembly back to starting position. The spring 101a is attached to and partially wound around a reel 165 formed on the ratchet wheel 127.

By reference to Figure 9 it will be noted that 70 the shaft 120, to which the ratchet wheel 127, selector 118, and commutator 133 are fixedly secured, is journaled in the plates 13a and 18a, and extends freely through an opening 166 in the panel 131. Commutator brushes 119 are 75

preferably formed from a single sheet of material, and the brushes 119 and 135 are clamped by the insulating discs 167 secured against a shoulder on the upper end of the shaft 120 by means of a nut 168 threaded onto the upper end of the shaft.

In the operation of the form of the invention just described, when applied to a game, the game is placed in condition for playing by closing the master switch 90a, and during the play, one of the switches S1, S2, etc. may be closed according to the skill of the operator. The closing of one of these control switches will establish a circuit through one of the contacts 133 and one of the arms of the brush 119, which, in Figures 5 and 10, is shown in its initial position. This will establish a circuit through the wire 86a, solenoid 46a, and wire 88a, back to the control switch, causing the solenoid 46a to attract the armature 45a, thus moving the drive bar 122 into position where the armature and selector assembly will be moved one step in advance of the initial position. Simultaneously the switch 55a will be opened, and the spring 124 will then draw the bar 122 back to its initial position. This operation will be repeated until the last arm of the brush 119 has moved across the live contact 133 onto a dead contact.

Thereupon the circuit through the solenoid 46a will be broken and the circuit through the motor 136 will be simultaneously established by the moving of the brush 135 onto the live contact 134. The motor 136 will then drive the bar 32a through the successive reciprocations, each one advancing the ejector 11a one step, until the ejector has made a complete revolution, whereupon the cam 148 will engage the lever 149 and cause the bar 122 to make one additional reciprocation, thus moving the brush 135 off the live contact and breaking the motor circuit.

It will now be understood that in both forms of the invention, the ejector is rotated a full revolution, and the number of tokens delivered depends on the opening of the gate mechanism, a single gate being used in one form of the invention and the variation being effected by variation in the length of time the gate is allowed to remain open, whereas, in the other form of the invention, each pocket of the ejector has its own gate, and the variation is effected by varying the number of gates which are open, some of the gates controlling pockets adapted to discharge a greater number of tokens than other pockets.

In each form of the invention, the mechanism which rotates the ejector also exerts more or less control over the commutator, in one case being the sole means for rotating the commutator, and in both cases being the means for moving the commutator through the last step which opens the motor circuit. In one case the commutator and ejector rotate simultaneously and in the other case the commutator-selector assembly completes its selecting operation prior to the operation of the ejector. In each form of the invention, the mechanism goes through a complete cycle of movement, including both selecting and ejecting operations, each time a control switch is closed, and is reset back to initial position before the next cycle of movement is allowed to commence. Among other advantages this makes it possible to employ the device successfully in a game wherein each play constitutes

the shooting of a single ball as contrasted to the playing of a number of balls.

The foregoing detailed description has been given for clearness of understanding only, and no unnecessary limitations should be understood therefrom, but the appended claims should be construed as broadly as permissible in view of the prior art.

I claim as my invention:

1. In an electric token delivery device, a token magazine, a rotatable ejector adapted to translate tokens from said magazine to a discharge point, electrically operated release mechanism at said discharge point for controlling the release of tokens from said ejector, a plurality of circuits variably controlling said release mechanism so as to vary the number of tokens delivered by said ejector during a predetermined cycle of operation, each circuit including an individual control switch and a control common to all of said circuits, said common control being adapted, when one of said circuits is energized by the closing of its individual control switch, to move a predetermined distance, varying in accordance with which switch is closed, and to thereupon open the energized circuit, and means for causing the ejector to make a complete revolution and to return to its initial position during each of such cycles of operation, said ejector having a series of pockets which carry a plurality of tokens to or past the discharge point on each cycle of operation during which the release mechanism allows a varying number of tokens to be discharged from one or more of said pockets.

2. In an electric token delivery device, a token magazine, a rotatable ejector adapted to translate tokens from said magazine to a discharge point, electrically operated release mechanism at said discharge point for controlling the release of tokens from said ejector, a plurality of circuits variably controlling said release mechanism so as to vary the number of tokens delivered by said ejector during a predetermined cycle of operation, each circuit including an individual control switch and one of a plurality of contacts, a rotatable commutator normally engaging said contacts, and adapted, when any one of said control circuits is energized, to rotate so as to finally disengage the contact of the energized circuit, and means for causing the ejector to make a complete revolution and to return to its initial position during each of such cycles of operation, said ejector having a series of pockets which carry a plurality of tokens to or past the discharge point on each cycle of operation during which the release mechanism allows a varying number of tokens to be discharged from one or more of said pockets.

3. In an electric token delivery device, a token magazine, a rotatable ejector adapted to translate tokens from said magazine to a discharge point, means for causing predetermined rotation of said ejector during each cycle of operation, electrically operated release mechanism at said discharge point for controlling the release of tokens from said ejector, a plurality of circuits variably controlling said release mechanism so as to vary the number of tokens delivered by said ejector during a predetermined cycle of operation, each circuit including an individual control switch and one of a plurality of contacts, a rotatable commutator normally engaging said contacts, means, energized by whichever of said circuits is energized, for advancing said commutator until the latter disengages the contact of

- the energized circuit and thereby opens said circuit, and means, energized at the end of the movement of said commutator, for causing the ejector to finish one complete revolution, said 5
ejector having a series of pockets which carry a plurality of tokens to or past the discharge point on each cycle of operation during which the release mechanism allows a varying number of tokens to be discharged from one or more of said 10 pockets.
4. In an electric token delivery device, a token magazine, a rotatable ejector adapted to translate tokens from said magazine to a discharge point, electrically operated release mechanism at 15 said discharge point for controlling the release of tokens from said ejector, a plurality of circuits variably controlling said release mechanism so as to vary the number of tokens delivered by said ejector during a predetermined cycle of operation, each circuit including an individual control switch and one of a plurality of contacts, a rotatable commutator normally engaging said contacts, and means initially energized by whichever of said circuits is energized, for rotating said 20 ejector through a complete revolution and for simultaneously rotating said commutator so as to disengage the contact of the energized circuit, said ejector having a series of pockets which carry a plurality of tokens to or past the discharge point on each cycle of operation during 25 which the release mechanism allows a varying number of tokens to be discharged from one or more of said pockets.
5. In an electric token delivery device, a token magazine, a rotatable ejector adapted to translate tokens from said magazine to a discharge point, electrically operated release mechanism at 30 said discharge point for controlling the release of tokens from said ejector, a plurality of circuits variably controlling said release mechanism so as to vary the number of tokens delivered by said ejector during a predetermined cycle of operation, each circuit including an individual control switch and one of a plurality of contacts, a 35 rotatable commutator normally engaging said contacts, means initially energized by whichever of said circuits is energized, for rotating said ejector through a complete revolution and for simultaneously rotating said commutator so as to 40 disengage the contact of the energized circuit, and means for maintaining a circuit through said rotating means after the control circuit is opened, for completing the rotation of the ejector, said ejector having a series of pockets which 45 carry a plurality of tokens to or past the discharge point on each cycle of operation during which the release mechanism allows a varying number of tokens to be discharged from one or more of said pockets.
6. In an electric token delivery device, a token magazine, electrically operated release mechanism located at a token discharge point for controlling the delivery of tokens from said magazine in varying numbers for a predetermined 50 cycle of operation, a rotatable commutator, a plurality of circuits for variably controlling said release mechanism, each circuit including a contact engageable with said commutator and a control switch for energizing said circuit as long as 55 the latter is completed through the commutator, said contacts being arranged to be successively disengaged by the commutator, whereby the number of tokens released by said release mechanism will vary depending upon which circuit is 60 energized, and electrical means, energized each 65

time any one of said circuits is energized, for translating tokens from the magazine to a discharge point, said ejector having a series of pockets which carry a plurality of tokens to or past the discharge point on each cycle of operation during which the release mechanism allows a varying number of tokens to be discharged from one or more of said pockets. 70

7. In an electric token delivery device, a token magazine, an ejector adapted to translate tokens from said magazine to a discharge point, electrically operated release mechanism controlling the release of tokens by said ejector, said mechanism including gate means at said discharge point normally restraining the release of tokens and electrical means for opening said gate means for varying portions of the cycles of operation of said ejector, so as to release varying numbers of tokens, a plurality of circuits controlling said electrical means, each circuit including an individual control switch and a control common to all of said circuits and adapted to open said circuits in successive order so as to vary the intervals of opening of said gate means, and electric motor means, energized each time one of the aforesaid circuits is energized for driving said ejector in uniform cycles of movement, said ejector having a series of pockets which carry a plurality of tokens to or past the discharge point on each cycle of operation during which the release mechanism allows a varying number of tokens to be discharged from one or more of said pockets. 75

8. In an electric token delivery device, a token magazine, an ejector adapted to translate tokens from said magazine to a discharge point, means for causing predetermined rotation of said ejector during each cycle of operation, electrically operated release mechanism controlling the release of tokens by said ejector, said mechanism including gate means at said discharge point normally restraining the release of tokens and electrical means for opening said gate means for varying portions of the cycles of operation of said ejector, so as to release varying numbers of tokens, a plurality of circuits controlling said electrical means, each circuit including an individual control switch and a control common to all of said circuits and adapted to open said circuits in successive order so as to vary the intervals of opening of said gate means, said ejector having a series of pockets which carry a plurality of tokens to or past the discharge point on each cycle of operation during which the release mechanism allows a varying number of tokens to be discharged from one or more of said pockets. 80

9. In an electric token delivery device, a token magazine, an ejector adapted to translate tokens from said magazine to a discharge point, electrically operated release mechanism at said discharge point controlling the release of tokens by said ejector, electrical means for driving said ejector in uniform cycles of movement, and electrical means for causing said release mechanism to effect release of tokens during varying portions of such cycles of movement, said last-mentioned means comprising a plurality of circuits, each including an individual switch and a control common to all of said circuits adapted to complete the one of said circuits that is closed by its individual switch, for a period, the duration of which varies for each of said circuits, said ejector having a series of pockets which carry a plurality of tokens to or past the discharge point on each cycle of operation during which the release mechanism allows a varying number of tokens to be discharged from one or more of said pockets. 85

anism allows a varying number of tokens to be discharged from one or more of said pockets.

10. In an electric token delivery device, a token magazine, a rotatable ejector adapted to translate tokens from said magazine to a point of discharge, an electric motor device for rotating said ejector in step-by-step movements, a rotatable commutator, a plurality of circuits, each including a control switch and a contact engaging said commutator, electrically operated discharge gate mechanism at said discharge point controlled by said circuits, and adapted to release a varying number of tokens from said ejector, depending upon which circuit is energized, said contacts being arranged to be successively disengaged by said commutator as the latter rotates, whereby the number of tokens released by said gate mechanism will vary, depending upon which of said circuits is energized by the closing of its individual control switch, said ejector having a series of pockets which carry a plurality of tokens to or past the discharge point on each cycle of operation during which the release mechanism allows a varying number of tokens to be discharged from one or more of said pockets.

11. In an electric token delivery device, a token magazine, an ejector adapted to translate tokens from said magazine to a discharge point, means for causing predetermined rotation of said ejector during each cycle of operation, electrically operated release mechanism controlling the release of tokens by said ejector, said mechanism including gate means at said discharge point normally restraining the release of tokens, and electrical means for opening said gate means, a plurality of circuits for variably controlling said electrical means, each circuit including an individual control switch and a control common to all of said circuits and adapted to open said circuits in successive order, the extent of release of tokens by said release mechanism varying in accordance with the interval between the energization of one of said circuits by the closing of the control switch thereof, and the opening of said circuit by the common control, said ejector having a series of pockets which carry a plurality of tokens to or past the discharge point on each cycle of operation during which the release mechanism allows a varying number of tokens to be discharged from one or more of said pockets.

12. In an electric token delivery device, a member having a discharge opening therein, a token magazine having a discharge mouth disposed above said member and offset from said opening, an ejector rotatably mounted above said member and having a series of pockets equidistant from the axis of rotation, adapted to translate tokens from said magazine to said discharge opening, means for causing predetermined rotation of said ejector during each cycle of operation, electrically operated gate means at the discharge point for closing said opening, and a plurality of remote-control circuits for variably controlling the opening of said gate means.

13. In an electric token delivery device, a member having a discharge opening therein, a token magazine having a discharge mouth disposed above said member and offset from said opening, an ejector rotatably mounted above said member and having a series of pockets equidistant from the axis of rotation, adapted to translate tokens from said magazine to said discharge opening, means for causing predetermined rotation of said ejector during each cycle of operation, electrically operated gate means at the discharge point for

closing said opening, and a plurality of remote-control circuits for variably controlling the opening of said gate means so as to vary the number of tokens delivered by said ejector during a given cycle of operation, each circuit including an individual control switch and a control common to all of said circuits and adapted, when one of said circuits is energized by the closing of its individual control switch, to successively open said circuits until it opens the energized circuit. 10

14. In an electric token delivery device, a member having a discharge opening therein, a token magazine having a discharge mouth disposed above said member and offset from said opening, an ejector rotatably mounted above said member and having a series of pockets equidistant from the axis of rotation, adapted to translate tokens from said magazine to said discharge opening, means for causing predetermined rotation of said ejector during each cycle of operation, a series of gates normally closing said pockets, an electrically operated selector located at the discharge point movable into a series of positions for opening one or more of said gates, and a plurality of remote-control circuits for variably controlling 25 said selector.

15. In an electric token delivery device, a member having a discharge opening therein, a token magazine having a discharge mouth disposed above said member and offset from said opening, an ejector rotatably mounted above said member and having a series of pockets equidistant from the axis of rotation, adapted to translate tokens from said magazine to said discharge opening, means for causing predetermined rotation of said ejector during each cycle of operation, a series of gates normally closing said pockets, said gates each having a projecting member, an electrically operated rotatable selector at the discharge point having a plurality of fingers of different length, selectively movable into the path of one or more of said projecting members, for opening one or more of said gates, and a plurality of remote-control circuits variably controlling said selector. 35

16. In an electric token delivery device, a token magazine, an ejector adapted to transport tokens from said magazine to a discharge point, electrically operated release mechanism at said discharge point for controlling the release of tokens from said ejector, a plurality of circuits for variably controlling said release mechanism, each of said circuits including a remote-control switch and a contact, a commutator including brush means initially engaging all of said contacts at once, means, energized by whichever of said circuits is energized, for rotating said commutator until the live contact has been disengaged by the commutator, means for actuating said ejector, and means for energizing said actuating means, including a brush carried by said commutator and positioned to engage said live contact after the same has been disengaged by said brush means, said ejector having a series of pockets which carry a plurality of tokens to or past the discharge point on each cycle of operation during which the release mechanism allows a varying number of tokens to be discharged from one or more of said pockets. 55

17. In an electric token delivery device, a token magazine, an ejector adapted to successively transport tokens from said magazine to a discharge point, means for causing predetermined rotation of said ejector during each cycle of operation, electrically operated release mechanism at said discharge point for controlling the release of 70

- tokens, a rotatable commutator, a plurality of circuits for variably controlling said release mechanism, each circuit including a contact engageable with said commutator and a control switch for energizing said circuit as long as the latter is completed through the commutator, said contacts being arranged to be successively disengaged by the commutator, whereby the number of tokens released by said release mechanism will 5 vary in response to the circuit that is energized, and electrical means, energized each time any one of said circuits is energized, for oscillating said commutator to circuit-breaking position, returning it to its initial position, said ejector having a 10 series of pockets which carry a plurality of tokens to or past the discharge point on each cycle of operation during which the release mechanism allows a varying number of tokens to be discharged from one or more of said pockets.
- 15 20. 18. In an electric token delivery device, a supporting member having a discharge opening therein, an ejector rotatably mounted above said opening and having a series of pockets therein, means for causing predetermined rotation of said 25 ejector during each cycle of operation, a token magazine offset from said discharging opening having a discharge mouth disposed above said ejector and adapted to deposit tokens in said pockets when the same are presented beneath 30 said mouth, a series of gates, one associated with each of said pockets for closing the same, a plurality of remote-control electric circuits having control switches therein, electrically controlled means at the discharge point operable through 35 the closing of said switches individually for causing the opening of a number of said gates depending upon which switch is closed, to thereby cause the discharge of said tokens in varying quantities having predetermined relation to the 40 individual switches.
19. In an electric token delivery device, a supporting member having a discharge opening therein, an ejector rotatably mounted above said opening and having a series of pockets therein,

means for causing predetermined rotation of said ejector during each cycle of operation, said ejector pockets being of varying token-holding capacity, a token magazine offset from said discharge opening having a discharge mouth disposed above said ejector and adapted to deposit tokens in said pockets when the same are presented beneath said mouth, a series of gates, one associated with each of said pockets for closing the same, a plurality of remote-control electric 10 circuits having control switches therein, electrically controlled means at the discharge point operable through the closing of said switches individually for causing the opening of a number of said gates depending upon which switch is 15 closed, to thereby cause the discharge of said tokens in varying quantities having predetermined relation to the individual switches.

20. In an electric token delivery device, a supporting member having a discharge opening 20 therein, an ejector rotatably mounted above said opening and having a series of pockets therein, means for causing predetermined rotation of said ejector during each cycle of operation, a token magazine offset from said discharge opening having a discharge mouth disposed above said ejector and adapted to deposit tokens in said pockets when the same are presented beneath said mouth, a series of gates, one associated with each of said pockets for closing the same, a plurality of remote-control electric circuits having control switches therein, electrically controlled means at the discharge point operable through the closing of said switches individually for causing the opening of a number of said gates depending upon which switch is closed, to thereby cause the discharge of said tokens in varying quantities having predetermined relation to the individual switches, said last means including a member 30 adapted to be projected into the path of movement of one or more of said gates as the latter are carried by the rotation of said ejector past said member.

BERT E. MILLS.
